RAIL FASTENER

William C. Woodings, Verona, Pa., assignor to
 Woodings-Verona Tool Works, Verona, Pa., a
 corporation of Pennsylvania

Application April 27, 1938, Serial No. 204,486

12 Claims. (Cl. 238—366)

This invention relates to fasteners for securing railroad rails in place on supporting cross ties.

It is among the objects of this invention to provide a rail fastener which is made in one piece, is inexpensive, durable, readily applied, is usable with an ordinary tie-plate, locked against loosening, adjustable for different pressures and for tie-plates and rail base flanges of different thicknesses, is provided with means for preventing over-driving, and which resiliently holds down the rail and also serves as a creep check.

In accordance with this invention a railroad rail is held in place by a fastener that has a vertical shank extending down through a tie-plate hole and into a cross tie. The upper end of the shank is provided with a laterally projecting head for bearing against the top of a rail base flange. The shank is formed from at least two substantially upright metal bars which are laterally offset relative to each other and at least one of which has at one edge a surface adapted to engage the bottom of the tie-plate adjoining the shank-receiving hole. The normal width of the shank, taken on a line between said bars on a level with the tie-plate engaging surface, is greater than the width of the tie-plate hole. To permit the shank to be inserted in the tie-plate hole, the bars are adapted to be canted sideways in opposite directions in order to reduce the width of the shank. The bars are preferably biased apart so as to tightly grip the tie-plate and the tie when driven into the openings therein.

The invention is illustrated in the accompanying drawings in which Fig. 1 is a fragmentary vertical section through a rail base, cross tie, and tie-plate, showing one form of my invention in elevation; Fig. 2 is a vertical section taken on the line II—II of Fig. 1; Figs. 3 and 4 are views, similar to the preceding figures, of a modified embodiment of the invention; Fig. 5 is a side view of another modification; Figs. 6 and 7 are views, similar to Figs. 1 and 2, of the fastener of Fig. 5 in operative position; Figs. 8 and 9 are similar views of a further modification of this invention; and Figs. 10, 11 and 12 are views, similar to Figs. 5, 6 and 7, of still another modified embodiment.

Referring to Fig. 1 of the drawings, a tie-plate 1 is mounted on top of a wooden cross tie 2, and may be provided transversely of its upper surface with a rib 3 forming an integral shoulder that defines one side of a rail seat and prevents lateral movement in that direction of the rail flanges 4 mounted on the seat. The tie-plate is provided with the usual square spike holes 6 at the edge of the rail base.

In order to hold the rail down on its seat in accordance with this invention a rail fastener, preferably made in one piece from a metal bar bent to shape, is disposed in a tie-plate hole 6 with its shank 7 extending downwardly into the cross tie. The shank is driven into position in the tie which has a preformed oversized spike-receiving hole 9 therein for that purpose. The upper end of the shank terminates in an integral extension in the form of a laterally projecting flattened loop 11 the inner end of which is preferably curved downwardly to form a bearing surface for engaging the top of the adjacent rail base flange 4.

The metal bar from which the fastener is made 15 is most suitably resilient, whereby when the fastener is driven into the tie its rail-engaging surface is distorted upwardly from its broken-line position shown in Fig. 1 and thereby biases the rail downwardly against its seat at all times. 20 The resiliency of the fastener also permits the usual slight rise and fall of the rail without raising the fastener as a whole and thereby loosening it in the cross tie. Loop 11 increases the resiliency of the fastener as a whole and distributes 25 the distortion of the bar over a greater area so that there is little likelihood of the fastener breaking.

It is a feature of this invention that the fastener shank is in the form of two substantially upright metal bars 12 and 13 one of which is provided in one edge with a notch 14, as shown in Fig. 2, the lower surface of which is adapted to engage the bottom of the tie-plate adjoining spike hole 6 when loop 11 engages the rail base and exerts 30 enough pressure on it to be distorted upwardly thereby. The notch extends upwardly along bar 12 far enough to permit the notch to straddle the tie-plate. The two bars are normally offset laterally in opposite directions relative to each other 35 to such an extent that the width of the shank taken on a line between the bars on a level with the lower surface of the notch is greater than the width of the hole. Each bar is narrower than the tie-plate hole so that when the two bars are 40 canted toward each other in opposite directions they can be inserted in that hole. When the shank is driven into the hole far enough to bring the lower surface of notch 14 below the bottom of the tie-plate, bar 12 springs sideways away from bar 13 whereby the lower surface of the notch engages the bottom of the tie-plate adjoining the shank-receiving hole and prevents the fastener 45 from working out of place. The upper surface of

the notch prevents the fastener from being overdriven.

The lower ends of the two bars may be substantially in contact with each other at all times, but their body portions are spaced apart and must be sprung toward each other in being driven into the spike hole. This causes the shank to have a still tighter fit in the tie-plate and cross tie.

10 This fastener is not only locked in place, but also exerts a constantly uniform pressure against the rail base flange. As a result, the fastener serves as an effective and dependable creep check that functions continuously. It is made in one 15 piece in an inexpensive manner, and is readily applied to ordinary tie-plates.

In the modification shown in Figs. 3 and 4, the shank is much longer than the one of Fig. 1, but the principal difference lies in the fact that both 20 of the shank bars are provided with notches 21 and 22. The fastener has been driven down far enough to cause notch 21 to grip the tie-plate, but notch 22 is shown in a functionless position. However, if it is desired that the fastener head 25 exert more pressure on the rail base flange, the outer bar 23 is driven down farther until notch 22 engages the tie-plate too. A similar fastener in such a position is shown in Figs. 6 and 7 when both notches grip the tie-plate and lock the fastener under heavy pressure. Fig. 5 discloses the 30 positions of the two notches 26 and 27 before the fastener is driven into position. Figs. 5 and 6 also show the lower end of one bar projecting under the lower end of the other bar to facilitate 35 driving of the fastener.

In the modified embodiments of this invention shown in Figs. 8 to 12 the shank bars are integrally connected at their lower ends instead of at 40 their upper ends. Nevertheless, the fasteners are locked in place in the same manner as those previously described herein. Fig. 8 shows a fastener having a reinforced rail-engaging head 31 formed from the laterally curved and superimposed upper portions of the shank bars.

45 In Fig. 10 the upper portion of each resilient shank bar is curved laterally, but only arm 32 is adapted to engage the rail base flange. The upper portion 33 of the outer bar is curved more sharply and its end only is adapted to bear against the top of arm 32. When this fastener is driven into operative position, as shown in Fig. 11, the end of upper arm 33 presses down tightly on arm 32 and aids it in holding the rail on its seat and preventing it from creeping.

50 According to the provisions of the patent statutes, I have explained the principle and construction of my invention, and have illustrated and described what I now consider to be its best embodiment. However, I desire to have it understood that, within the scope of the appended 55 claims, the invention may be practiced otherwise than as specifically illustrated and described.

I claim:

1. A rail fastener comprising a shank adapted 60 to be inserted in a tie-plate hole, and a laterally projecting head adapted to bear against the top of a rail base flange, said shank being in the form of at least two substantially upright metal bars at 65 least one of which has at one edge a surface adapted to engage the bottom of the tie-plate adjoining the shank-receiving hole, the normal width of the shank taken on a line between said bars on a level with said surface being greater than said hole, and said bars being adapted to be canted edgewise in opposite directions longitudinally 70 of the rail to reduce said normal width of the shank in order to permit the shank to be inserted in the tie-plate hole.

nally of the rail to reduce said normal width of the shank in order to permit the shank to be inserted in the tie-plate hole.

5 2. A rail fastener comprising a shank adapted to be inserted in a tie-plate hole, said shank being in the form of two substantially vertical metal bars terminating at their upper ends in laterally projecting portions forming a head adapted to bear against the top of a rail base flange, at least one of said bars having at one edge a surface adapted to engage the bottom of the tie-plate adjoining the shank-receiving hole, the normal width of the shank taken on a line between said bars on a level with said surface being greater than said hole, and said bars being adapted to be canted edgewise in opposite directions longitudinally 10 of the rail to reduce said normal width of the shank in order to permit the shank to be inserted in the tie-plate hole.

15 3. A rail fastener comprising a shank adapted to be inserted in a tie-plate hole, said shank being in the form of two substantially vertical metal bars terminating at their upper ends in a laterally projecting top the outer end of which is adapted to bear against the top of a rail base flange, at least one of said bars having at one edge a surface adapted to engage the bottom of the tie-plate adjoining the shank-receiving hole, the normal width of the shank taken on a line between said bars on a level with said surface being greater than said hole, and said bars being adapted to be canted edgewise in opposite directions longitudinally 20 of the rail to reduce said normal width of the shank in order to permit the shank to be inserted in the tie-plate hole.

25 4. A rail fastener comprising a shank adapted to be inserted in a tie-plate hole, and a laterally projecting head adapted to bear against the top of a rail base flange, said shank being in the form of two substantially vertical metal bars, each having at one edge a surface adapted to engage the bottom of the tie-plate adjoining the shank-receiving hole, said surfaces being on opposite sides of the shank, the normal width of the shank taken on a line between said bars on a level with 30 one of said surfaces being greater than said hole, and said bars being adapted to be canted edgewise in opposite directions longitudinally of the rail to reduce said normal width of the shank in order to permit the shank to be inserted in the tie-plate hole.

35 40 5. A rail fastener comprising a shank adapted to be inserted in a tie-plate hole, and a laterally projecting head adapted to bear against the top of a rail base flange, said shank being in the form of two substantially vertical metal bars, at least one of which has at one edge a notch the lower surface of which is adapted to engage the bottom of the tie-plate adjoining the shank-receiving hole, the normal width of the shank taken on a line between said bars on a level with said surface being greater than said hole, and said bars being adapted to be canted edgewise in opposite directions longitudinally 45 of the rail to reduce said normal width of the shank in order to permit the shank to be inserted in the tie-plate hole.

50 55 6. A rail fastener comprising a shank adapted to be inserted in a tie-plate hole, said shank being in the form of two substantially vertical resilient metal bars terminating at their upper ends in laterally projecting portions forming a resilient head adapted to bear against the top of a rail base flange, at least one of said bars having at one edge a notch the lower surface of which is adapted to engage the bottom of the 60 rail to reduce said normal width of the shank in order to permit the shank to be inserted in the tie-plate hole.

tie-plate adjacent the shank-receiving hole, the normal width of the shank taken on a line between said bars on a level with said surface being greater than said hole, and said bars being adapted to be canted edgewise in opposite directions longitudinally of the rail to reduce said normal width of the shank in order to permit the shank to be inserted in the tie-plate hole.

7. A rail fastener comprising a shank adapted to be inserted in a tie-plate hole, said shank being in the form of two substantially vertical resilient metal bars terminating at their upper ends in a laterally projecting flattened loop the outer end of which is adapted to bear against the top of a rail base flange, at least one of said bars having at one edge a notch the lower surface of which is adapted to engage the bottom of the tie-plate adjacent the shank-receiving hole, the normal width of the shank taken on a line between said bars on a level with said surface being greater than said hole, and said bars being adapted to be canted edgewise in opposite directions longitudinally of the rail to reduce said normal width of the shank in order to permit the shank to be inserted in the tie-plate hole.

8. A rail fastener comprising a shank adapted to be inserted in a tie-plate hole, and a laterally projecting head adapted to bear against the top of a rail base flange, said shank being in the form of two substantially vertical metal bars each having at one edge a notch the lower surface of which is adapted to engage the bottom of the tie-plate adjacent the shank-receiving hole, said notches being on opposite sides of the shank, the normal width of the shank taken on a line between said bars on a level with one of said surfaces being greater than said hole, and said bars being adapted to be canted edgewise in opposite directions longitudinally of the rail to reduce said normal width of the shank in order to permit the shank to be inserted in the tie-plate hole.

9. A rail fastener comprising a shank adapted to be inserted in a tie-plate hole, and a laterally projecting head adapted to bear against the top of a rail base flange, said shank being in the form of two substantially vertical metal bars, each having at one edge a surface adapted to engage the bottom of the tie-plate adjoining the shank-receiving hole, said surfaces being on opposite sides of the shank at different levels, the normal width of the shank taken on a line between said bars on a level with one of said surfaces being greater than said hole, and said bars being adapted to be canted edgewise in opposite directions longitudinally of the rail to reduce said normal width of the shank in order to permit the shank to be inserted in the tie-plate hole.

10. A rail fastener comprising a shank adapted to be inserted in a tie-plate hole, and a laterally projecting head adapted to bear against the top of a rail base flange, said shank being in the form of two substantially vertical metal bars, each having at one edge a surface adapted to engage the bottom of the tie-plate adjoining the shank-receiving hole, said surfaces being on opposite sides of the shank with the innermost surface lower than the outermost, the normal width of the shank taken on a line between said bars on a level with one of said surfaces being greater than said hole, and said bars being adapted to be canted edgewise in opposite directions longitudinally of the rail to reduce said normal width of the shank in order to permit the shank to be inserted in the tie-plate hole.

11. A rail fastener comprising a shank adapted to be inserted in a tie-plate hole, and a laterally projecting head adapted to bear against the top of a rail base flange, said shank being in the form of at least two substantially upright metal bars at least one of which has at one edge a surface adapted to engage the bottom of the tie-plate adjoining the shank-receiving hole, the normal width of the shank taken on a line between said bars on a level with said surface being greater than said hole, the bars being biased apart to make the shank thicker than the width of said hole, and said bars being adapted to be canted edgewise in opposite directions longitudinally of the rail and sprung toward each other to reduce the normal width and thickness of the shank in order to permit the shank to be inserted in the tie-plate hole.

12. A rail fastener comprising a shank adapted to be inserted in a tie-plate hole, said shank being in the form of two substantially upright resilient metal bars connected together at their lower ends with their upper end portions curved laterally to form a head adapted to bear against the top of a rail base flange, the end of the upper end portion of the outer bar being adapted to bear against the upper curved portion of the inner bar and bias it downwardly, at least one of said bars having at one edge a surface adapted to engage the bottom of the tie-plate adjoining the shank-receiving hole, the normal width of the shank taken on a line between said bars on a level with said surface being greater than said hole, and said bars being adapted to be canted edgewise in opposite directions longitudinally of the rail to reduce said normal width of the shank in order to permit the shank to be inserted in the tie-plate hole.

WILLIAM C. WOODINGS.
